[57] CLAIM

The ornamental design for an anchored golf tee, as shown and described.

DESCRIPTION

FIG. 1 is a perspective view of an anchored golf tee showing my new design;

FIG. 2 is a front elevational view thereof, the rear elevational view being a mirror image;

FIG. 3 is a top plan view thereof;

FIG. 4 is a bottom view thereof;

FIG. 5 is a left side elevational view thereof; and,

FIG. 6 is a right side elevational view thereof.

The broken line showing of a golf ball in FIGS. 1 and 2 is for illustrative purposes only and forms no part of the claimed design.

The tether is drawn fragmentary to show indeterminate length.

FIG. 1
